PRESS

Clifford N. Benander, Meriden, Conn., assignor,
by mesne assignments, to Monowatt Electric
Corporation, a corporation of Rhode Island

Application October 19, 1935, Serial No. 45,760

5 Claims.

(Cl. 18—16)

The present invention relates to presses of the type suitable for producing molded parts.

The object of my invention is to provide an improved construction and arrangement in a press of this type, and for a consideration of what I believe to be novel and my invention attention is directed to the accompanying description and the claims appended thereto.

In the accompanying drawing, Fig. 1 is an elevation partly broken away of a press embodying my invention showing the press in the open position; Fig. 2 is a fragmentary elevation showing the press in the closed position; Fig. 3 is a sectional view taken on line 3—3 of Fig. 1; and Fig. 4 is a perspective view of two of the links used to operate the press.

Referring to the drawing, the press is supported on a frame which comprises a base plate 1 supported by four columns 2. To the upper side of the base plate are secured four rectangular guide posts 3 to the upper ends of which is bolted a stationary platen 4. A movable platen 5 is arranged to slide toward and away from the stationary platen 4 on the guide posts 3. The adjacent faces of the stationary and movable platens are arranged to carry the complementary parts 6 and 7 of a suitable mold.

As shown in Fig. 3, the movable platen 5 is of channel-shaped section having depending flanges 8 connected by a web portion 9. Adjacent the inner side of each of the flanges 8 are angular guides 10 having one side secured to a shoulder 11 on the web portion 9 by screws 12 and having the other side contacting the inner surface of the adjacent flange. Below the guides 10 are plates 13 which are secured to the lower edges of the flanges by screws 14. The plates 13 and the guides 10 provide guides on the under side of the movable platen which are spaced apart in the direction of movement of the movable platen.

The linkage for reciprocating the removable platen comprises two links 15 which are respectively pivoted at one end on pins 16 which are carried by brackets 17 on opposite sides of the base plate 1. The other end of each of the links 15 extends between the forked end 18 of a link 19 and is pivoted thereto by means of a pin 20. The other end 21 of each of the links 19 is also forked and is pivotally connected by a pin 22 to a block 23 fixed to the upper end of a piston rod 24. To the lower end of the piston rod is fixed a piston 25 which slides within a cylinder 26. The piston is reciprocated by fluid conducted from a source of fluid pressure by a supply conduit 26a selectively connected to conduits 26b

and 26c connected respectively to each end of the cylinder. The supply of fluid is controlled by a four-way valve 26d which is arranged so that when fluid is supplied to one of the conduits 26b or 26c fluid is discharged from the other of the conduits through a discharge conduit 26e. Suitable packing 27 is arranged between the piston rod and the cylinder. The cylinder is supported on the columns 2 by a plate 28. The force for reciprocating the movable platen is transmitted to the movable platen through rolls 29 which project from opposite sides of the link 19 adjacent the pin 20. As shown by Fig. 3, these rolls extend between the parallel guides formed by the guides 10 and the plates 13.

In the operation of the press, the linkage causes a gradual increase in leverage as the press moves from the open position shown in Fig. 1 to the closed position shown in Fig. 2. During the closing movement, the rolls 29 bear against the guides 10. At the start of the closing movement, the leverage ratio is substantially one to one, and the leverage gradually increases to a maximum as the links 19 approach a horizontal position, slightly above the position shown in Fig. 2. It is apparent from an inspection of Fig. 2 that there is a considerable range during which substantially the maximum leverage is exerted on the movable platen. This range extends from a position in which the links are slightly below the position shown in Fig. 2 to a position in which the links are inclined slightly above the horizontal. The press therefore accommodates itself to a rather large variation in stroke without adjustment and without substantial variation in pressure. On the reverse stroke, the rolls 29 bear against the plates 13 and the force exerted on the movable platen is the same as during the pressure stroke. This means that the maximum pressure on the press is available for separating the parts of the mold. This feature is of particular importance in the manufacture of parts from molded insulating material, since the force required to break the mold is substantially the same as the force required to press the parts of the mold together.

What I claim as new and desire to secure by Letters Patent of the United States, is:

1. A press for producing molded parts comprising a frame, a stationary platen, a movable platen 50 slidable in the frame, complementary parts of a mold carried by said platens, a pair of guides on the movable platen spaced apart in the direction of movement of the movable platen, a toggle including a pivoted lever having a member ad- 55

jacent its pivot point slidable between said guides for reciprocating the movable platen, said member engaging one of the guides during the pressure stroke and the other guide during the reverse stroke of the movable platen, a piston for moving said lever to effect reciprocation of the movable platen, and fluid pressure means for positively reciprocating the piston.

2. A press for producing molded parts comprising a frame, a stationary platen, a movable platen slidable in the frame, complementary parts of a mold carried by said platens, a piston, two links pivoted respectively at one end to opposite sides of the frame, two links each pivoted at one end to the piston and at the other end to one of said first links, members projecting from each side of said second links adjacent the pivotal connection between said first and said second links, parallel guides on said movable platen between which said members slide, said members engaging one of said guides during the pressure stroke of the piston and the other of said guides during the reverse stroke of the piston, and fluid pressure means for positively reciprocating the piston.

25 3. A press for producing molded parts comprising a frame, a stationary platen, a movable platen slidable in the frame, complementary parts of a mold carried by said platens, two links pivoted respectively at one end to opposite sides of the frame, two links each pivoted at one end to one of said first links and having the other ends adjacent each other, means including a piston for reciprocating said other ends toward and away from the stationary platen, guides on the movable platen spaced apart in the direction of movement of the movable platen, members on said second links adjacent the pivot points between the first and second links and slidable between said guides for moving the movable platen, said members engaging one of said guides during the pressure stroke and the other of said guides during the reverse stroke of the movable platen, and fluid

pressure means for positively reciprocating said piston.

4. A press for producing molded parts comprising a frame, a stationary platen, a movable platen slidable in said frame, complementary parts of a mold carried by said platens, said movable platen having depending flanges connected by a web portion, guides on the web portion adjacent each of the flanges, plates secured to the flanges extending over said guides, a lever having members slidable between said guides and said plates for reciprocating the movable platen, said members engaging said guides during the pressure stroke and said plates during the reverse stroke of the movable platen, a piston for moving said lever to effect reciprocation of the movable platen, and fluid pressure means for positively reciprocating the piston.

5. A press for producing molded parts comprising a frame, a stationary platen, a movable platen slidable in said frame, complementary parts of a mold carried by said platens, said movable platen having depending flanges connected by a web portion, a pair of guides adjacent the inner surface of each of the flanges, said guides being spaced apart in the direction of movement of the movable platen, two links pivoted respectively at one end to opposite sides of the frame, two links each pivoted at one end to said first links and having the other ends adjacent each other, means including a piston for reciprocating said other ends toward and away from the stationary platen, members projecting from opposite sides of said second links between said pairs of guides for moving the movable platen, said members engaging the guides adjacent the web portion of the movable platen during the pressure stroke and engaging the other guides during the reverse stroke of the movable platen, and fluid pressure means for positively reciprocating said piston.

CLIFFORD N. BENANDER.
